(57) **CLAIM**

I claim the ornamental design for a combined brush and spray unit for washing toilets, as shown and described.

DESCRIPTION

FIG. 1 is a front, top and side perspective view of the combined brush and spray unit for washing toilets embodying the design of the present invention.

FIG. 2 is a side elevational view thereof, the opposite side being a mirror image.

FIG. 3 is a front elevational view thereof.

FIG. 4 is a rear elevational view thereof.

FIG. 5 is a bottom plan view thereof; and,

FIG. 6 is a top plan view thereof.
